UNITED STATES PATENT OFFICE.

DABNEY COSBY, OF COLUMBIA, VIRGINIA.

MESSAGE-HOLDER.

No. 909,870.

Specification of Letters Patent.

Patented Jan. 19, 1909.

Application filed May 23, 1907. Serial No. 276,169.

To all whom it may concern:

Be it known that I, DABNEY COSBY, a citizen of the United States, residing at Columbia, in the county of Fluvanna and State of Virginia, have invented a new and useful Improvement in Message-Holders, of which the following is a specification.

This invention relates to message holders for delivering messages to the engineer of the train when in motion, the object being to provide a holder so constructed that the message can be folded and inserted into the same so that it can be readily grasped by the engineer when passing a station without any danger of the operator being thrown off his feet by being caught hold of by the engineer while trying to grasp the message out of his hand.

Another object of my invention is to provide a holder which is very simple and cheap in construction, and one which will hold the message so that it can be readily slipped out of the same when grasped by the hand.

With these and other objects in view, the invention consists in the novel features of construction, combination and arrangement of parts hereinafter fully described and pointed out in the claim.

In the accompanying drawings, I show a perspective view of my improved holder which is formed of a single piece of wire looped centrally and twisted upon itself to form a handle J the ends being bent out-

wardly to form a fork, the extreme ends being looped and twisted upon themselves to form spaced clamping rings between which the message is adapted to be securely held.

It will be seen that an envelop can be easily and quickly placed between the spaced clamping rings J which will securely hold the same by frictional contact of the rings so that all danger of the envelop becoming accidentally detached is prevented.

From the foregoing description, it will be seen that I have provided a message holder which is exceedingly cheap and simple in construction and one which is formed of a single piece of wire and which is so bent and twisted as to form clamping rings at its end which will securely hold the envelop so that it can be readily grasped at the center.

Having thus fully described my invention, what I claim as new and desire to secure by Letters Patent is:—

A message holder comprising a single piece of wire bent and twisted upon itself to form a handle having outwardly extending curved end portions forming a fork, the ends of said portions being coiled and twisted upon themselves to form spaced clamping rings for holding a message.

DABNEY COSBY.
